DAM FORMING ATTACHMENT

Leonard Taylor, Fort, Okla.

Application February 18, 1937, Serial No. 126,673

3 Claims. (Cl. 97—55)

The present invention relates to new and useful improvements in dam forming attachments for listers of the tractor attached type and has for its primary object to provide, in a manner as hereinafter set forth, a device of this character which is adapted to form spaced dams in the furrows or ditches left by the lister shovels or plows thereby preventing excessive washing away of the soil by rain.

Another very important object of the invention is to provide an attachment of the aforementioned character embodying novel means for connecting the dam forming members to the wheels of the tractor for periodical actuation thereby.

Other objects of the invention are to provide a dam forming attachment of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation, showing the invention.

Figure 2 is a view in rear elevation of the portions of the operating mechanism which are mounted on the tractor.

Figure 3 is a vertical section view, taken substantially on the line 3—3 of Fig. 1.

Figure 4 is a view in horizontal section, taken substantially on the line 4—4 of Fig. 1.

Figure 5 is a detail view in perspective of one of the trips.

Referring now to the drawings in detail, it will be seen that the embodiment of the invention which has been illustrated comprises pairs of bearings 1 which are rigidly secured in any suitable manner on the rear axle housing 2 of a conventional tractor 3 between the rear wheels 4 of said tractor and the differential housing 5. Journaled in the bearings 1 are shafts 6 the inner ends of which terminate in upstanding arms 7. At their outer ends, the shafts 6 terminate in angular levers 8 which extend adjacent the wheels 4. Trips 9 are mounted on the wheels 4 for engagement with the levers 8, said trips being secured by suitable bolts or clamps 10.

The reference numeral 11 designates beams which are pivotally connected to the lister beam 55 12 for swinging movement in a vertical plane

through the medium of pairs of metallic straps or bars 13. The beams 11 are rigidly secured between the pairs of bars 13, as at 14, and said pairs of bars straddle the lister beams 12 and are pivotally connected thereto, as at 15. Mounted on the free rear ends of the beams 11 are shanks 16 which carry transversely arranged, inclined scraping discs or elements 17. The shanks 16 are adjustable on the beams 11 to permit the inclination of the scraper discs 17 to be varied as desired.

The beams 11 are connected to the arms 7 in a manner to be raised thereby through the medium of chains 18. The angle of pull of the chains 18 on the beams 11 is modified to facilitate the lifting of said beams through the medium of rods 19 which are secured between the pairs of bars 13, as at 20. The chains 18 are secured to the rearwardly and upwardly extending rods 19 by suitable means, such as adjustable nuts 21. Suitable springs 22 extend forwardly from the arms 7 to the tractor 3 to prevent said arms from being pulled rearwardly by the weight of the chains 18 when the lister and the attachment are raised.

It is thought that the operation of the invention will be readily apparent from a consideration of the foregoing. Elements 17 follow the lister plows 23 and scrape up an accumulation of soil in the furrows or ditches left by said plows. With each revolution of the tractor wheels 4 the trips 9 engage the levers 8 and swing the arms 7 forwardly in a manner to lift the beams 11 through the medium of the chains 18, thus disengaging the elements 17 from the furrows or ditches and leaving the accumulations of dirt 35 which have been scraped up by said elements 17 in said furrows or ditches in a manner to form dams at spaced points. Of course, after the trips 9 pass out of engagement with the levers 8 the elements 17 return by gravity to the furrows or 40 ditches. As hereinbefore stated, the inclination of the elements 17 may be adjusted as desired through the medium of the adjustably mounted shanks 16. The usual subsoiler spouts 24 are left on the lister for engagement beneath the pairs 45 of pivotally mounted bars 13 for lifting the beams 11 when the beams 12 are lifted.

It is believed that the many advantages of a dam forming attachment constructed in accordance with the present invention will be readily 50 understood and although a preferred embodiment of the device is as illustrated and described, it is to be understood that changes in the details of construction and in the combination and arrangement of parts may be resorted to which will 55

fall within the scope of the invention as claimed.

What is claimed is:—

1. A dam forming attachment for wheeled listers comprising a beam pivotally connected to the lister for swinging movement in a vertical plane, a scraping element mounted on said beam and adapted to travel in the ditch made by the lister plow, and means operatively connecting the beam to one of the wheels of the lister for periodically lifting said element out of the ditch, said means including a shaft rotatably mounted on the lister, an arm projecting from said shaft, a flexible member connecting the beam to said arm, a lever projecting from the shaft, and a trip on said one wheel engageable with the lever for actuating the shaft and the arm in a direction to lift the beam.
2. A dam forming attachment for wheeled listers comprising, a pair of transversely aligned bearings mounted on the rear axle housing of the lister adjacent one of the rear wheels, a shaft journaled in said bearings, an arm on the inner end of said shaft, a lever on the outer end of the shaft, a pair of bars pivotally secured to the lister beam on opposite sides thereof for swinging movement in a vertical plane, a beam rigidly secured between said bars, a shank adjustably

mounted on the second named beam, a transverse, inclined scraping disc mounted on said shank and adapted to travel in the ditch left by the lister plow, a trip mounted on said one wheel of the lister and engageable with the lever for swinging the arm forwardly, and a chain connecting the arm to the second named beam for periodically lifting the scraping element out of the ditch.

3. A dam forming attachment for wheeled listers comprising a pair of bars pivotally connected to the lister beam on opposite sides thereof for swinging movement in a vertical plane, a beam rigidly secured between said bars, a scraping element mounted on the second named beam and adapted to travel in the ditch left by the lister plow, a rod secured between the bars and extending upwardly and rearwardly therefrom, an arm mounted for swinging movement on the tractor, a chain connecting the second named beam to said arm for lifting the scraping element out of the ditch, said chain being secured, at an intermediate point, to the rod for forming an angle in said chain, and means operatively connecting the arm to one of the wheels of the tractor for periodic actuation thereby.

LEONARD TAYLOR.
